Primary Examiner—T. Chase Nelson*Assistant Examiner*—Mark Cavanna(74) Attorney, Agent, or Firm—Fish & Richardson P.C.(57) CLAIM

The ornamental design for a shelf for a ceiling mounted medical supply system, substantially as shown and described.

DESCRIPTION

FIG. 1 shows a perspective view of the design;

FIG. 2 shows a front view of the design;

FIG. 3 shows a rear view of the design;

FIG. 4 shows a right side view of the design;

FIG. 5 shows a left side view of the design;

FIG. 6 shows a top plan view of the design; and,

FIG. 7 shows a bottom plan view of the design.

The features shown in broken lines are environmental structure and form no part of the claimed design.
